UNITED STATES PATENT OFFICE.

MORRIS MAYER, OF ST. LOUIS, MISSOURI.

HUMIDOR.

1,094,081.

Specification of Letters Patent. Patented Apr. 21, 1914.

Application filed July 14, 1913. Serial No. 778,939.

To all whom it may concern:

Be it known that I, MORRIS MAYER, a citizen of the United States of America, and resident of the city of St. Louis and State 5 of Missouri, have invented certain new and useful Improvements in Humidors, of which the following is a full, clear, and exact description, reference being had to the accompanying drawings, forming a part of 10 this specification.

My invention relates to a humidor for holding a box of cigars, the humidor being one more particularly intended for use by traveling men, and having for its object to so 15 construct a humidor that a cigar box therein and the internal parts of the humidor will be held in fixed positions, notwithstanding shaking to which the humidor may be subjected when being carried in traveling cases.

Figure I is a top or plan view of my humidor, with the lid open and partly broken away. Fig. II is a vertical longitudinal section through the humidor, with the lid closed and a cigar box confined therein. 20 Fig. III is a vertical cross section through the humidor, with the lid closed, and a cigar box therein.

The body A of my humidor and the lid B are preferably made of sheet metal, but any 30 other suitable material may be used for their production, it being desirable that the material should be of light weight and thin, so that the humidor will be unburdensome to carry, and unbulky.

A moistener pad compartment for holding a moistener pad C is formed within the humidor by a pair of spaced walls 1, extending vertically from the bottom of the body A, between which the pad C is confined, the walls 1 being preferably provided with perforations 2, permitting moisture to pass laterally through said walls beneath a cigar box thereabove, in addition to rising from the moistener pad. The moistener pad is held in its compartment by a retainer rod 3, one end of which is loosely pivoted to a hinge ear 4, attached to one of the pad compartment walls 1. The retainer rod 3 is provided at its free end with 45 a finger 5, which engages a perforated spring catch 6, secured to the second pad compartment wall.

7 designates posts secured to the bottom of the humidor body near the ends of the 55 humidor, and extending upwardly therefrom to a plane higher than that occupied by

the top edges of the pad compartment walls 1, these posts having points 8 at their upper ends adapted to be embedded in the bottom of a cigar box placed in the humidor. To 60 limit the entrance of the points of the posts 7 into the bottom of the cigar box, so that they may not pass therethrough to the injury of cigars in the box, I provide box supporting posts 9 attached to the pad compartment walls 1, these supporting posts being of slightly less height than the pointed posts 7, which, by their entrance into the bottom of the cigar box, serve to prevent lateral movement of the box relative to the walls of the humidor body A. The posts 9 are also of service in supporting a cigar box so that it is spaced from the moistener pad and the pad compartment walls to permit circulation of air between said pad and its compartment walls, and prevent the box from becoming wet, as distinguished from becoming moistened by vapor rising from the moistener pad.

A cigar box, when placed in my humidor, is seated upon the posts 9 and 7 to be supported and held from movement in the manner described, and to hold the cigar box firmly seated on said posts, I provide a pressure spring 10, attached to the lid of the humidor and seating upon the lid of the cigar box when the humidor lid is closed. The spring 10 is preferably of double arm form, as shown, and extends longitudinally of the humidor, so that its arms will exert 80 downward pressure at opposite sides of the longitudinal center of the cigar box, with the result of causing the points of the post 7 at each end of the humidor to be retained in the bottom of the cigar box. A suitable 85 catch b is carried by the lid B, for engagement with the body of the humidor to hold the lid closed.

It is sometimes desirable to admit more moisture into a cigar box than will penetrate through a closed cigar box, as, for instance, when the cigars are dry previous to their introduction into the humidor; and I, therefore, provide my humidor with means for holding the lid of a cigar box 100 open to a slight degree while in the humidor. This means comprises a separating block 11, preferably of inverted U-shape, which may be fitted to the front wall of the cigar box, and hold the cigar box lid in uplifted position, as seen in Figs. II and III. The separating block is attached to the body of the 105 110

humidor by a chain 2, or other suitable flexible connection, which is of sufficient length to allow the separating block to be applied to cigar boxes of different heights when in the humidor.

spaced walls, a spring carried by said lid adapted to bear upon a cigar box seated upon said supporting posts, and pointed posts 7 extending vertically from the bottom of said body entering into the bottom of the cigar box to hold it from lateral movement. 15

I claim:—

A humidor, comprising a body, a lid for said body, a moistener pad compartment in said body, comprising spaced walls between 10 which a moistener pad is held, cigar box supporting posts 9 extending above said

MORRIS MAYER.
